Primary Examiner—Ted Shooman*Assistant Examiner*—C. Tuttle*Attorney, Agent, or Firm*—Julie Blackburn[57] **CLAIM**

The ornamental design for a toenail clipper, as shown and described.

DESCRIPTION

FIG. 1 is a front perspective view of the clipper;
 FIG. 2 is a right side elevational view of the clipper;
 FIG. 3 is a left side elevational view of the clipper;
 FIG. 4 is a top plan view of the clipper;
 FIG. 5 is a bottom plan view of the clipper;
 FIG. 6 is a front elevational view of the clipper; and
 FIG. 7 is a back elevational view of the clipper.
 The undisclosed and partially obscured surfaces of the design follow the contours of the portions visible.
